(57) CLAIM

The ornamental design for a barbecue grill brush, as shown and described.

DESCRIPTION

FIG. 1 is a front elevational view of a barbecue grill brush showing my new design;

FIG. 2 is a rear elevational view thereof;

FIG. 3 is a side view thereof;

FIG. 4 is an enlarged bottom view thereof;

FIG. 5 is an enlarged top view thereof; and,

FIG. 6 is a perspective view thereof.

The side not illustrated is a mirror image of the side illustrated in FIG. 3 and the scraper blade illustrated in dashed lines does not form part of the claimed design.
